(57) **CLAIM**

The ornamental design for a medical dilator, as shown and described.

DESCRIPTION

FIG. 1 is a perspective view of a medical dilator in accordance with the present invention;

FIG. 2 is a front elevation view of the medical dilator shown in FIG. 1;

FIG. 3 is a top plan view of the medical dilator shown in FIG. 1; and,

FIG. 4 is a bottom plan view of the medical dilator shown in FIG. 1.

The interior contours, as shown in FIG. 3, follow the exterior contours visible throughout the views.
